UNITED STATES PATENT OFFICE.

ALEXANDER RISPEL, OF CHICAGO, ILLINOIS, ASSIGNOR OF ONE-HALF TO LOUIS H. LIEDTKE, OF CHICAGO, ILLINOIS.

DOOR CHECK AND CLOSER.

1,053,222.

Specification of Letters Patent. Patented Feb. 18, 1913.

Application filed March 13, 1912. Serial No. 683,425.

To all whom it may concern:

Be it known that I, ALEXANDER RISPEL, a citizen of the United States, residing at Chicago, in the county of Cook and State 5 of Illinois, have invented a new and useful Door Check and Closer, of which the following is a specification.

The present invention relates to improvements in door checks and closers, the primary 10 object of the invention being the provision of a means for locking the spring actuated arms against the tension of the spring in full extended position to retain the door in open position and an auxiliary means for 15 locking the said arms in intermediate position, the main mechanism being the usual form of fluid and spring controlled door check and closer, although it is to be understood that the same may be used in connection 20 entirely with a spring actuated door check and closer.

A further object of the present invention is the provision in a liquid and spring actuated door check and closer, having mounted 25 upon the spindle within the casing a frame carrying a spring actuated projected bolt which is combined and disposed to co-act with an adjustable stop mounted within the 30 wall of the casing to lock the door in any intermediate position.

With the foregoing and other objects in view which will appear as the description proceeds, the invention resides in the combination and arrangement of parts and in 35 the details of construction hereinafter described and claimed, it being understood that changes in the precise embodiment of the invention herein disclosed can be made within the scope of what is claimed without 40 departing from the spirit of the invention.

In the drawings Figure 1 is a top plan view of the complete door check and holder. Fig. 2 is a section taken on line 2—2 thereof. Fig. 3 is a section taken on line 3—3 of Fig. 45 2. Fig. 4 is a section taken on line 4—4 of Fig. 2. Fig. 5 is a section taken on line 5—5 of Fig. 2. Fig. 6 is a detail side elevation of the frame carrying the auxiliary lock for the spindle. Fig. 7 is a detail perspective view of the adjustable locking lug *per se*. Fig. 8 is a detail view of the under side of the casing of the spindle connecting arm showing the spring actuated bolt carried thereby. Fig. 9 is a detail view of the 50 cover and the adjacent portion of the main

casing, showing the adjusting device for regulating the retention of the door in open position. Fig. 10 is a perspective view of the sealing plate and means for connecting the frame carrying the intermediate position locking bolt.

Referring to the drawings, the numeral 1 designates the casing whose lower reduced end 2 is the liquid chamber while the upper enlarged end 3 is the mechanism carrying 60 chamber. The partition 4 is disposed to substantially hermetically seal the liquid chamber 2 and thereby separate the liquid from the mechanism carrying chamber of the casing.

Mounted within the liquid carrying chamber 2 is the plunger 5 which is provided with diametrically disposed grooves 6 in which are adapted to fit the pin 7 and the adjusting screw 7' mounted in the sleeve 8, said 70 adjusting screw 7' also providing a means for draining or filling the liquid chamber. By this means it will be seen that the plunger 5 is mounted so as to be permitted only a sliding movement within the chamber 2. 80 Disposed in the lower end of the plunger 5 is a valve 9 to control the ports 10, which permits the proper sliding movement of the plunger 5, the same providing a by-pass for the passage of the liquid within the chamber 85 2 from one side to the other of the piston 5 so as to act in the manner of a dash-pot and ease the movement of the spindle 13 which is the main actuating spindle of the device. The lower end of the spindle 13 has the 90 squared upper portion 13' and has its lower cylindrical end connected to the worm or spiral 12 which coacts with the grooves 11 of the plunger 5, so that the rotation of the spindle 13 will impart the desired up and 95 down movement to the plunger 5 within the chamber 2.

The greater portion of the spindle 13 projected within the chamber 3, is shouldered as at 14, while sealing the upper open end of 100 the casing is a lid or cover 15 above which the spindle 13 projects. As clearly shown in Fig. 9, the lid 15 is provided with the depending flange 16 which carries the adjusting screw 17, which is adapted to align 105 with and engage one of the sockets 18 formed in the body of the casing 1, so that the said lid may be adjusted and retained in any desired adjustment by means of the screw 17 and one of the sockets 18. The lid 15 110

is provided with the enlarged concentric aperture 19 for the reception of the sleeve 20, whose upper disk portion is in reality a gear 21, disposed to be engaged by the 5 adjusting screw 22 carried by the inner arm 23, which is connected at 24 to the upper end of the actuating spindle 13. The arm 23 has pivotally connected to its outer end the extensible arm 25, which carries at its free 10 end the door engaging plate 26, while the casing 1 carries the jamb or wall engaging plate 26', whereby the device may be properly attached for operation.

Formed integral with and upon the top 15 of the cover 13, is a lug 27 which is at a diametrically opposite point to the screw 17, while within the underside of the arm 23 is disposed the spring actuated lug 28, which is in the path to abut and engage the 20 lug 27 of the lid, and when the arm is in the dotted position as shown in Fig. 1, the lug 27 will hold the arm extended against the tension of the spring 32. In order to 25 properly mount the spring actuated lug 28, a recess is formed in the underside of the arm as at 28', the same being sealed by a plate 29, while the spring 30 is incased therein so as to normally hold the lug 28 in the position as shown in Fig. 2.

30 The sleeve 20 is provided with a longitudinal slot 31 for the reception of the inner terminal of the convolute spring 32, whose outer terminal is seated within the groove 33 formed in the wall of the casing 1 and within the chamber 3 thereof. By 35 this means the spring exerts a tension to revolve the spindle 13 and lower the plunger 5 and thus slightly retard the closing action imparted to the arms 23 and 25 by 40 means of the spring 32, the opening action being against the tension of the spring and imparting an upward movement to the plunger 5.

In order to form an auxiliary locking device, so as to lock the spindle and consequently the arms 23 and 25 in any intermediate position, so that the door may be held ajar, the two washers 34 and 35 are mounted upon the spindle 13 above the dia- 50 phragm or partition 4 and have interposed therebetween the coiled spring 36, which exerts a normal tension upward so as to hold the washer 35 seated within the cavity 37 of the spring projected lock carrying frame 55 38, which is clearly shown in detail in Figs. 4 and 6. This frame 38 is provided with the two sliding pins 39 which carry the plate 40 having the bolt or lug 41, the two springs 42 being disposed upon the pins 39 60 and exerting an outward tension to normally hold the bolt or lug 41 in the position as shown in Fig. 4 with the plate 40 in engagement with the standard 43 of the frame 38. Another plate 44 seals the top of 65 the frame 38 and permits, when desirable,

ready access to the pins 39 and springs 42. This plate is provided with the rectangular aperture 44', (Fig. 10) to fit upon the rectangular portion 13' of the spindle or shaft 13 so that the frame 38 is fixed for rotation 70 with the spindle or shaft.

In the wall of the casing adjacent to the chamber 3, is formed a segmental slot 45 which is sealed by means of a slidable plate 46, semi-circular in cross section, and which 75 has connected thereto the reduced lug 48 of the adjustable locking lug 49. This locking lug is disposed to be slid to assume any of the various positions regulated by the length of the slot 45, so as to be disposed 80 in the path to abut the projection 41, and as the plate 44 holds the frame 38 fixedly with the spindle or shaft 13 the spindle 13 can be locked at any intermediate position, to hold the said spindle against the 85 tension of the spring 32 so that the folding arms 23 and 25 may retain the door at any position between closed and fully open. In order to lock the abutment 49 in the desired position, and at the same time lock the plate 46 in such position, the screw 50 engages the reduced portion 48 of the device shown in Fig. 7, and projects exteriorly of the casing through the slot 45, the same being provided with the milled disk 51, so that the 90 same may be rotated to exert a tension upon the washer 52 which is disposed upon the screw 51 and spans the slot 45 so that the inner face of the abutment 49 is drawn toward the said washer 52, and the parts are 100 clamped in any desired position.

What is claimed is:

1. A door check and closer, having a liquid and a spring chambered casing, an actuating spindle, a spring mounted in the 105 spring chamber and connected to the spindle, a plunger operably connected to the spindle within the liquid chamber, said casing forming a mounting connection for the device, a folding arm connected to the 110 spindle and carrying the other mounting connection, coacting means carried by the casing and arm to lock the arm against the tension of the spring, and coacting means carried by the spindle and casing for locking the spindle and arm in intermediate position against the tension of the spring.

2. A door check and closer, having a liquid and a spring chambered casing, an actuating spindle, a spring mounted in the 120 spring chamber and connected to the spindle, a plunger operably connected to the spindle within the liquid chamber, said casing forming a mounting connection for the device, a folding arm connected to the 125 spindle and carrying the other mounting connection, coacting means carried by the casing and arm to lock the arm against the tension of the spring, a frame mounted upon the spindle within the spring chamber of 130

the casing and provided with a spring ejected locking bolt, and adjustable means 5 slidably mounted in the wall of the casing adjacent said frame for coaction with the spring actuated bolt to lock the spindle in intermediate position against the tension of the spring.

3. A door check and closer, having a casing, a spring actuated spindle, a folding arm 10 connected to the spindle, an abutting means carried by the arm, an adjustable stop carried by the casing and disposed in the path to engage the abutting means of the arm to hold the arm in extended position against 15 the tension of the spring, and coacting means carried by the spindle and casing to lock the spindle and arm at intermediate points against the tension of the spring.

4. A door check and closer, having a casing, a spring actuated spindle, a folding arm 20 connected to the spindle, coacting means carried by the casing and arm to lock the arm extended and against the tension of the spring, a spring actuated bolt carried by the 25 spindle within the casing, and an adjustable

means mounted in the wall of the casing in the path to engage said spring actuated bolt to lock the spindle and arm at intermediate points against the tension of the spring.

5. A door check and closer, having a casing, a spring actuated spindle, a folding arm connected to the spindle, a lug carried by the arm adjacent to the casing, an adjustable lug 30 connected to the casing and disposed in the path of the lug of the arm to lock the arm extended and against the tension of the spring, a spring projected bolt mounted upon the spindle within the casing, and adjustable means disposed in the wall of the casing and in the path to engage said spring 35 actuated bolt to lock the spindle and arm at intermediate points against the tension of the spring.

In testimony that I claim the foregoing as my own, I have hereto affixed my signature in the presence of two witnesses.

ALEXANDER RISPEL.
